[57] CLAIM

The ornamental design for a toy rotor element, as
shown and described.

DESCRIPTION

FIG. 1 is a top perspective view of the toy rotor ele-
ment showing my new design,

FIG. 2 is a bottom perspective view thereof,

FIG. 3 is a top plan view thereof,

FIG. 4 is a bottom plan view thereof,

FIG. 5 is a side elevational view thereof; the side oppo-
site being a mirror image, and

FIG. 6 is another side elevational view thereof; the side
opposite being a mirror image.
